United States Patent Office

Des. 183,976
Patented Nov. 25, 1958

183,976

BATTERY TERMINAL CONNECTOR

Ernest G. Prantis, New Britain, Conn.

Application May 28, 1957, Serial No. 46,377

Term of patent 14 years

(Cl. D26—1)

Fig. 1.

Fig. 2.

Fig. 3.

Fig. 4.

Fig. 5.

Fig. 1 is a top plan view of a battery terminal connector, showing my new design.

Fig. 2 is a front elevational view.

Fig. 3 is a side elevational view.

Fig. 4 is a rear elevational view.

Fig. 5 is a bottom plan view thereof.

I claim:

The ornamental design for a battery terminal connector, as shown.
